UNITED STATES PATENT OFFICE

2,488,806

RADIATOR FILTER

Clarence E. Crowder, Oro Grande, Calif.

Application June 21, 1948, Serial No. 34,262

7 Claims. (Cl. 123—170)

1

This invention relates to new and useful improvements in filters and the primary object of the present invention is to provide a radiator filter that prevents the radiator core of a vehicle from becoming clogged.

Another important object of the present invention is to provide a radiator filter that is applied between the radiator and the motor block or water jacket of a vehicle or internal combustion engine including a baffle plate having a screened opening, said baffle plate being so disposed in a vertically inclined position that sedimentation will be washed or forced from the screened opening thus retaining the screened opening free from clogging.

A further object of the present invention is to provide a radiator filter that is interposed between a vehicle radiator and motor block including a pressure conduit that extends between the inlet of the filter and rear portion of the motor block to effectively and efficiently flush the motor block to prevent sedimentation forming therein due to the added pressure acting upon the normal water flow.

A still further aim of the present invention is to provide a radiator filter of the aforementioned character that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary side elevational view of an internal combustion engine having the present radiator filter installed in the outlet from its water jacket;

Figure 2 is a side elevational view of the present invention;

Figure 3 is a longitudinal vertical sectional view taken substantially on the plane of section line 3—3 of Figure 2; and,

Figure 4 is a top plan view of Figure 3, and with parts broken away for the convenience of explanation.

Referring now to the drawings in detail, wherein for the purpose of illustration, there is disclosed a preferred embodiment of the present invention, the numeral 10 represents a hollow body of any suitable non-corrosive material hav-

2

ing a pair of openings 12 to which there is rigidly attached the flanged portions 14 of an outlet nipple 16 and an inlet nipple 18 that are co-axial in a vertically inclined plane so that the same will incline toward the radiator 20 of a vehicle or internal combustion engine 22 having a water jacket or block 24.

Fixed to the spaced parallel side walls 26 of the body 10, and to the inner faces of each of the walls 26, is an upper and lower pair of spaced angle strips 28 and 30, which are disposed at a vertically inclined angle to communicate with an opening 32 provided in the rear wall 34 of the body 10.

15 Slidably engaged between the pairs of guides or strips 28 and 30, is a substantially rectangular baffle plate 36 that divides the body 10 into two compartments. The plate 36 is formed with a substantially rectangular opening 38 adjacent the openings 12 and a screen or filter unit 40 is fixed to one face of the plate 36 and registers with the opening 38.

20 Removably secured to the outer face of the end wall 34, and closing the opening 32 is a holding plate 41 that bears against the upturned edge or flange 42 of the plate 36, and a sealing gasket 44 is disposed between the plate 41 and wall 34 to prevent liquid from passing outwardly from the body 10 between the wall 34 and plate 41.

25 An annular angle member 46 is fixed to the bottom wall 48 of the body 10 about an opening 50 provided in the wall 48 and is frictionally embraced about the upper open end of the sediment cup 52 that is preferably constructed of a transparent material, such as plastic or glass.

30 Embracing the body 10 and the cup 52, is a substantially rectangular, open frame 54 the lower side 56 of which engages concaved grooves provided in a plurality of blocks or lugs 58 carried by the closed end of the cup 52.

The upper side 60 of the frame 54 engages a further concaved groove provided in an adjustable bolt 62 that is supported by a lug 64 and nut 66 which are fixed to the upper wall of the body 10.

35 Fixed to one side wall of the body 10, is a conduit 68 having an intake end 70 that extends into the nipple 18. This conduit 68 is connected by a tubing 72, as at 74, to the rear portion of the water jacket 24, as shown in Figure 1 of the drawings, to provide a means for supplying a fluid pressure from the engine to the rear portion of the water jacket to move forwardly and prevent sedimentation from collecting on the inner walls of the jacket 24. The conduit or tubing 72 thereby provides a flushing line to the rear

portion of the conduit from the forward portion of the engine.

In practical use of the present invention, the outlet nipple 16 is coupled by a sleeve 18 to the radiator nipple 78, and the inlet nipple 18 is 5 coupled as at 80 to the outlet nipple 82 of the engine 22.

The water entering the body 10 through the nipple 18 will engage the baffle 36 and will contact the screen 40 before passing through the nipple 16, thus removing sediment in the water which will fall into the cup 52.

It should be noted, that the baffle 36 is so inclined that the water will be directed downwardly and forwardly to remove sediment collecting 15 on the screen 40.

Pressure on the nipple 18, from the engine 22, will enter the conduit 68 to be directed into the engine 22 to increase the normal pressure in the engine's water system and the velocity of the 20 water in the water system thus preventing sediment from collecting on the inner walls of the jacket 24.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In the cooling system of a vehicle including a radiator having an intake nipple and a cylinder block having an outlet nipple; a radiator filter comprising a hollow body having an inlet port engageable with the intake nipple of the radia-

tor and an outlet port engageable with the outlet nipple of the cylinder block, means for screening fluid passing through the body, means for collecting sediment remaining in the body, and a pressure line between said body and the rear portion of the cylinder block.

2. A radiator filter comprising a hollow body having an inlet and outlet, a sedimentation chamber carried by the body, means mounted in said body for screening liquid passing therethrough, and a pressure conduit leading from said body to a cylinder block.

3. The combination of claim 2 wherein said means includes an inclined baffle opposing said inlet and outlet, said baffle having an opening, and a screen unit carried by the baffle registering with said opening.

4. The combination of claim 2 wherein said means includes a baffle plate having a screened opening, means carried by said body supporting said plate, and means retaining said plate disposed within said body.

5. The combination of claim 4 wherein said supporting means includes guides fixed in said body slidably engaging said plate.

6. The combination of claim 4 wherein said last mentioned means includes a holding plate removably secured to said body, said body having an access opening closed by said holding plate.

7. The combination of claim 2 wherein said conduit includes an intake end communicating with the inlet of said body.

CLARENCE E. CROWDER.
